UNITED STATES PATENT OFFICE.

SAMUEL BLUMENFELD, OF CHICAGO, ILLINOIS.

FASTENING FOR WARDROBE-TRUNKS.

1,215,469.

Specification of Letters Patent. Patented Feb. 13, 1917.

Application filed February 21, 1916. Serial No. 79,636.

To all whom it may concern:

Be it known that I, SAMUEL BLUMENFELD, a citizen of the United States of America, and a resident of Chicago, county 5 of Cook, and State of Illinois, have invented certain new and useful Improvements in Fastenings for Wardrobe-Trunks, of which the following is a specification.

The main objects of this invention are 10 to provide an improved fastening or latching means for wardrobe trunks.

An illustrative embodiment of this invention is shown in the accompanying drawings, in which—

15 Figure 1 is a perspective of the improved trunk in an open position and with the drawers and garment rack removed, and with a portion of one wall panel broken away to show the mounting of the latching 20 means.

Fig. 2 is an enlarged detail showing the arrangement of the latch operating means.

In the construction shown in the drawings, the trunk comprises two box-like parts 25 1 and 2 of size and proportion common in wardrobe trunks, said parts being swingably connected together by hinges 3. The hinges 3 are provided with springs 4 which normally urge the two parts of the trunk 30 to an open position.

The trunk is adapted to stand on end and when in that position is supported on casters in the form of ball bearings 5.

The part 1 of the trunk is provided with 35 a hinged hasp 6 of usual form adapted to engage in a socket 7 on the part 2. Latching means are provided for releasably securing the trunk parts together when the hasp 6 is unlocked from its socket, and comprise a bar 8 slidably mounted in guides 9 on the inner side of part 1, said bar having latching arms 10 rigidly mounted thereon.

The outer ends of the arms 10 are beveled 45 to form inclined faces 11 immediately back of which the arms are cut away so as to form hooks 12. Suitable means such as staples 13 are provided on the other part of the trunk, and are positioned so as to 50 be engaged by the hooked ends 12 of arms 10 when the trunk is in a closed position, the bar 8 being normally urged downward (Fig. 1) by a spring 14 attached to one end thereof. The other end of the bar 8 55 is provided with a bent portion 15 which

extends through a slot 16 in the side of the part 1, said slot being located directly beneath the hasp 6 so as to be covered thereby when the hasp is in locked position.

Means for sliding the bar 8 against the 60 action of its spring for disengaging the latching means are provided, and comprise a handle 17 pivotally mounted on the bent end 15 of bar 8. The handle 17 is also located beneath and thereby protected by the 65 hasp 6 when said hasp is closed.

In the operation of the trunk, it is set 70 on end in the usual manner. The hasp 6 may then be unlocked from socket 7 and swung outward, thereby uncovering the 70 handle 17. Said handle may then be grasped and lifted upward (Fig. 1) the bent end 15 of the bar traveling in slot 16, thereby sliding the bar 8 against the action of spring 14.

Longitudinal movement of the bar 8 75 shifts the latching arms 10 and disengages the hooked ends 12 thereof from the staples 13.

Although but one specific embodiment of 80 this invention is herein shown and described, it is to be understood that the construction may be altered or details omitted without departing from the spirit of this invention as defined by the following claim. 85

I claim:

A wardrobe trunk comprising two box-like parts hinged together, a hasp for locking the two parts together, a bar slidably mounted on the inner side of one of said 90 parts, said one part having a slot therein located beneath and covered by said hasp when said hasp is in locked position, a bent end on said bar for traveling in said slot, latching hooks carried by said bar, means 95 on the other part of the trunk for being engaged by said latching hooks, yielding means for normally urging said latching hooks into engagement with said first mentioned means when the two trunk parts are 100 in closed position, and an operating handle on said bent end of the slidably mounted bar for shifting said bar to disengage said latching means.

Signed at Chicago this 18th day of Feb., 105
1916.

SAMUEL BLUMENFELD.
